US0D1046812S

(12) **United States Design Patent** (10) Patent No.: **US D1,046,812 S**
(45) Date of Patent: ** Oct. 15, 2024

(54) **HEADPHONES**

(71) Applicant: **MerchSource, LLC**, Irvine, CA (US)

(72) Inventors: **Greg Thüne**, Los Angeles, CA (US);
Keith Lawrence Covey, Costa Mesa, CA (US)

(73) Assignee: **MerchSource, LLC**, Irvine, CA (US)

(**) Term: **15 Years**

(21) Appl. No.: **29/862,709**

(22) Filed: **Dec. 12, 2022**

(51) LOC (14) Cl. **14-01**

(52) U.S. Cl.

USPC **D14/205**

(57) **CLAIM**

The ornamental design for headphones, as shown and described.

DESCRIPTION

FIG. 1 is a rear, side perspective view of the headphones showing the present design.

FIG. 2 is a front perspective view of the headphones of FIG. 1.

FIG. 3 is a side elevation view of the right side of the headphones of FIG. 1.

FIG. 4 is a side elevation view of the left side of the headphones of FIG. 1.

FIG. 5 is a top plan view of the headphones of FIG. 1.

FIG. 6 is a bottom plan view of the headphones of FIG. 1.

FIG. 7 is a rear elevation view of the headphones of FIG. 1; and,

FIG. 8 is a front elevation view of the headphones of FIG. 1.

In the drawings, the broken lines depict portions of the headphones that form no part of the claimed design.

1 Claim, 6 Drawing Sheets
